UNITED STATES PATENT OFFICE.

CHARLES T. LYONS AND HARRY W. BELL, OF SEATTLE, WASHINGTON, ASSIGNORS TO THE DURABLE MAT COMPANY, OF SEATTLE, WASHINGTON.

DIE PRESS.

Application filed October 18, 1926. Serial No. 142,187.

The invention is a die press for removing rectangular shaped blocks from used motor vehicle tires:

The object of the invention is to provide means for efficiently removing blocks from the walls of motor vehicle tires.

Another object of the invention is to provide means for removing rectangular shaped blocks from the walls of used motor vehicle 10 tires, which minimizes the waste.

And a further object of the invention is to provide a compound die and means for operating the same which will efficiently remove rectangular shaped blocks with 15 curved ends, from the walls of motor vehicle tires, and instantly separate the blocks from the waste.

With these ends in view the invention embodies a combination die, pins co-operating 20 with the said die, cams for operating the said pins, and a press for operating the said die.

Other features and advantages of the invention will appear from the following description taken in connection with the drawings, wherein:

Figure 1 is a view showing a punch press.

Figure 2 is a detail view showing the arrangement of the dies, and pins and cams 30 for operating the said dies.

Figure 3 is a view showing the face of the dies and one arrangement of them.

Figure 4 is a view showing a single die as it may be used.

Figure 5 is a similar view showing a 35 double die.

Figure 6 is a view showing one of the rectangular shaped blocks that may be stamped from the tire, or the like.

In the design shown, the press which is indicated by the numeral 1 is provided with an eccentric arm 2 which operates a carriage 3, and in the carriage 3 is a cam shaft 4 that may be operated by a chain 5, which 40 is indicated in dotted lines. This cam shaft is shown more clearly in Figure 2 and the cams which are indicated by the numeral 6 engage heads 7 of vertical pins, as shown. The pins are provided with springs 8 which 45 hold them in the upward position and these pins operate in and between the dies, which are indicated by the numeral 9. The outer shell of the die is of a rectangular shape

with curved ends, as shown in Figure 4 and in this die are tubular members 10 which 55 form the small circular opening as indicated by the numeral 11 adjacent the ends of the block, which is indicated by the numeral 12 and shown in Figure 6. Inside of the tubes 10 are pins 13 which are operated by 60 the cams 6 and springs 8, as hereinbefore described, and in the center of the die 9 is a pin 14 with a plate 15 on its lower end, which is also operated by the springs and 65 cams and at the ends of the die are other pins 16 which are also operated by the cams and springs. Below the dies and on the table of the press is a block of lignum-vitæ, as indicated by the numeral 17.

In the design shown the dies are arranged 70 as shown in Figure 3 so that three blocks may be stamped out with one operation and the dies are arranged on a slight curve to conform to the curvature of a tire so that the maximum number of blocks may be 75 stamped out of a tire. It is also understood that only one die may be used, as shown in Figure 4 and also that they may be arranged in pairs, as shown in Figure 5, or in any other grouping desired. The dies 80 may also be of any suitable shape, with pointed or square ends, or with the sides corrugated, or shaped in any suitable manner.

It is understood that other changes may 85 be made without departing from the spirit of the invention, one of which changes may be in the use of other types of dies, another may be in the use of other means for holding and operating the dies, and still another 90 may be in the use of any other suitable means for removing these blocks from tires.

The construction will be readily understood from the foregoing description. In use the dies may be arranged as shown, and a section of a motor vehicle tire placed upon the block 17 directly below the dies. The carriage 3 may then be tripped so that the dies will be forced through the wall of the tire and immediately the cams will force the pins 16 downward to force the tire away from the exterior of the dies. At the same time the dies will force the pins 13 downward to force the small circular members that are cut from the openings 11 out of the 105 tubes 10. As soon as this operation is com-

pleted the cams operating the pins 14 will force these pins downward and also the plates 15 and these will remove the blocks 12 from the dies. This particular arrangement of pins and cams provides a very efficient die which removes the block and instantly separates it from the waste. It is understood that the same arrangement of pins and cams may be used with the dies as shown in Figures 4 and 5 or with any suitable arrangement of the dies. It will be observed that the lower edges of the dies are curved and sharpened so that they actually cut through the material instead of endeavoring to punch the blocks out.

Having thus fully described the invention what we claim as new and desire to secure by Letters Patent, is:

1. A machine for stamping blocks from motor vehicle tires comprising a frame, a hard wood bed plate positioned on the frame, a plurality of vertically movable dies angularly positioned in relation to each other, in an arc having a common radius, a plurality of independently operated plungers cooperating with the said dies, a plurality of cams arranged on a cam shaft for operating the said plungers independent of each other and independent of the dies, an ec-

centric for operating the said dies, and driving means for operating the said eccentric and cams. 30

2. A machine for stamping blocks from motor vehicle tires comprising a frame, a plurality of vertically movable dies, a plurality of independently operated plungers cooperating with the said dies, a plurality of cams arranged on a cam shaft for operating the said plungers independent of each other and independent of the dies, an eccentric 35 for operating the said dies, and driving means for operating the said eccentric and cams. 40

3. A machine for stamping blocks from motor vehicle tires comprising a frame, a hard wood bed plate positioned on the frame, a plurality of vertically movable dies, a plurality of independently operated plungers cooperating with the said dies, a plurality of cams arranged on a cam shaft for operating 45 the said plungers independent of each other and independent of the dies, an eccentric for operating the said dies, and driving means for operating the said eccentric and cams. 50

In testimony whereof we affix our signatures.

CHARLES T. LYONS.
HARRY W. BELL.
